US00D731309S

(12) **United States Design Patent**
Lee et al.

(10) **Patent No.:** US D731,309 S
(45) **Date of Patent:** ** *Jun. 9, 2015

(54) **MEDICATE CONTAINER**

(71) Applicant: **Juno Technologies, LLC**, Palm Beach Gardens, FL (US)

(72) Inventors: **Richard M. Lee**, Volcano, CA (US); **Thomas Guschke**, Palm Beach Gardens, FL (US)

(73) Assignee: **Juno Technologies LLC**, Palm Beach Gardens, FL (US)

(*) Notice: This patent is subject to a terminal disclaimer.

(**) Term: **14 Years**

(21) Appl. No.: **29/467,345**

(22) Filed: **Sep. 18, 2013**

Related U.S. Application Data

(62) Division of application No. 29/435,578, filed on Oct. 25, 2012, now Pat. No. Des. 690,199.

(57) **CLAIM**

The ornamental design for a medicate container, as shown and described.

DESCRIPTION

FIG. 1 is a front perspective view of a medicate container in accordance with a preferred embodiment of our new design; FIG. 2 is a front elevation view thereof; FIG. 3 is a rear elevation view thereof; FIG. 4 is a top plan view thereof; FIG. 5 is a bottom plan view thereof; FIG. 6 is a left side elevation view thereof; and, FIG. 7 is a right side elevation view thereof. The broken lines in the figures are for the purpose of showing environmental structure and form no part of the claimed design.

1 Claim, 6 Drawing Sheets
